United States Patent Office

Des. 208,150
Patented July 25, 1967

208,150

VEHICLE GRILLE

Alfred B. Sanchez, P.O. Box 117-A,
Sandia, Tex. 78383

Filed Dec. 1, 1966, Ser. No. 4,877

Term of patent 3½ years

(Cl. D14—18)

The dominant features of my design reside in the portions shown in full lines.

I claim:

The ornamental design for a vehicle grille, as shown and described.
